UNITED STATES PATENT OFFICE.

ANDRZEJ ARENDARCZYK, OF NEWARK, NEW JERSEY.

HAT-PIN FASTENER AND POINT PROTECTOR.

1,004,963.

Specification of Letters Patent.

Patented Oct. 3, 1911.

Application filed July 8, 1911. Serial No. 637,423.

To all whom it may concern:

Be it known that I, ANDRZEJ ARENDARCZYK, a subject of the Emperor of Austria-Hungary, residing at Newark, in the county of Essex and State of New Jersey, have invented certain new and useful Improvements in Hat-Pin Fasteners and Point Protectors, of which the following is a specification, reference being had therein to the accompanying drawing.

This invention relates to a hat pin fastener and point protector, and the objects of my invention are to provide a device that can be easily and quickly mounted upon the pointed end of a hat pin to lock the hat pin within a hat and prevent its accidental displacement, and, to provide a device of the above type that will protect the pointed end of the pin and prevent pedestrians from being injured from coming into contact with the protruding end of the pin.

Further objects of my invention are to furnish a device of the above type with a novel gripping mechanism that is easily and quickly manipulated, and to accomplish the above results by a mechanical construction that is simple and durable, and inexpensive to manufacture.

With the above and other objects in view, the invention resides in the novel construction, combination, and arrangement of parts to be hereinafter specifically described and then claimed.

Reference will now be had to the drawing, wherein:-

Figure 1 is a side elevation of the device as applied to a hat pin; Fig. 2 is a plan of the same, Fig. 3 is a longitudinal sectional view of the device.

A device in accordance with this invention comprises an oblong housing, having side plates 1 and 2 and end plates 3 and 4, these plates having the ends thereof formed integral with the outer ends of the plates 1 and 2 bent outwardly and flared to provide a head 5. The end plate 4 has integral arms 6 bent upwardly in proximity to the edges of the plates 1 and 2, to round off the head 5 and prevent the fingers from entering between the plates 1 and 2.

The plate 1 intermediate the ends thereof is provided with apertured ears 7 bent toward the plate 2 and into parallelism to receive a transverse pivot pin 8. Pivoted upon the pin 8 is a lever 9 having the inner end thereof provided with a taper-

ing pin 10, and the outer end 11 thereof bent to extend through a longitudinal slot 12 provided therefor in the flared end of the plate 1. The pin 10 is adapted to engage in an opening 13 provided therefor in the pointed end 14 of a hat pin 15. The hat pin 15 extends through an opening 16 in the end wall 3, said opening being of a greater diameter than the diameter of the pin.

The inner side of the plate 2 is provided with a transverse rib 17, and with a guide lug 18, said rib being located adjacent to the ears 7 and the guide lug 18 at a point intermediate said ears and the end plate 4. The guide lug 18 has an opening 19 to receive the pointed end of the pin, and the rib 17 is adapted to engage a shoulder 20 formed by cutting away the pointed end of the pin 15, as at 21.

Arranged against the inner sides of the flared ends of the plates 1 and 2 is a leaf spring 22, having one end thereof anchored at the guide lug 18, and the opposite end thereof engaging the inner side of the lever 9 adjacent to the slot 12, whereby the outer end of the lever will be normally forced outwardly and the inner end thereof into engagement with the hat pin 15.

By pressing upon the outer end 11 of a lever 9, the pin 15 can be inserted in the device, the inward movement of said pin being limited by the pointed end thereof engaging in the guide lug 18. By limiting the inward movement of a pin, the shoulder 20 is in proximity to the rib 17, and if the shoulder does not engage the rib and prevent withdrawal of the pin 15, it is only necessary to rotate the pin until the shoulder 20 engages the rib. By then releasing the outer end of a lever, the tapered pin 10 enters the opening 13, and the end of a pin 15 will be forced into engagement with the rib 17. When any outward movement of the pin 15 is attempted, the rib 17 engaging the shoulder 20 relieves the pin 10 of any stresses or strains.

With a little practice, the manner of manipulating the device upon the end of a hat pin is soon understood, and the form of the housing guards the pointed end of a pin, while the mechanism within the housing prevents the device from becoming accidentally displaced relatively to the hat pin. The device can be made of light and durable metal and the head 5 is susceptible to any

ornamentation that does not interfere with the movement of the lever 9.

What I claim is:

The combination with a hat pin having 5 the end thereof cut away to provide a shoulder, of a housing adapted to receive the pointed end of said hat pin, a lever pivotally mounted in said housing and having one end thereof protruding from said 10 housing, a rib arranged within said housing and adapted to engage the shoulder of said hat pin, and means within said housing and

engaging said lever and adapted to retain said lever in engagement with said pin, whereby the shoulder of said pin will be 15 held in engagement with the rib of said housing.

In testimony whereof I affix my signature in the presence of two witnesses.
